UNITED STATES PATENT OFFICE.

FRANK HAMILTON PULSIFER, JR., OF AUBURN, NEW YORK.

DESIGN FOR A RADIATOR.

SPECIFICATION forming part of Design No. 21,177, dated November 17, 1891.

Application filed August 19, 1891. Serial No. 403,137. Term of patent 7 years.

To all whom it may concern:

Be it known that I, FRANK HAMILTON PULSIFER, Jr., a citizen of the United States, residing at Auburn, in the county of Cayuga 5 and State of New York, have invented and produced a new and original Design for Steam and Hot-Water Radiators; and I do hereby declare the following to be a full, clear, and exact description of the same, reference being 10 had to the accompanying drawings, forming a part thereof.

The drawings represent a front view in Figure 1 and an edge view in Fig. 2 of a radiator illustrating my design.

15 The leading feature of my design consists in the arrangement of raised ribs upon the surface of the radiator, said ribs being in short lengths and inclined to produce the appearance of inclined steps and broken spirals 20 surrounding the body of the radiator.

In said drawings, A represents the body of the radiator. The surface of said body has

thereon a series of short steps or ribs a parallel to each other, but inclined relatively to the general direction given to the body of the 25 radiator, and between the ribs a are a series of ribs a², that have a portion of their length parallel with the ribs a upon the front and rear faces of the radiator and a portion a³ which extends squarely across the edge of the 30 radiator and forms broken spirals thereon, the arrangement of the ribs thus presenting to the eye the combined appearance of inclined steps and broken spirals upon the smooth surface of the body of the radiator. 35

What I claim is—

The design for a radiator, as herein shown and described.

In testimony whereof I affix my signature in presence of two witnesses.

FRANK HAMILTON PULSIFER, JR.
